UNITED STATES PATENT OFFICE.

GABRIEL GERARDY, OF BLACKWELL, OKLAHOMA TERRITORY, ASSIGNOR
OF ONE-HALF TO E. Y. ALKIRE, OF BENDENA, KANSAS.

DISK-SHARPENER.

No. 821,096.

Specification of Letters Patent.

Patented May 22, 1906.

Application filed June 5, 1905. Serial No. 263,858.

To all whom it may concern:

Be it known that I, GABRIEL GERARDY, a citizen of the United States, residing at Blackwell, in the county of Kay, Oklahoma Territory, have invented certain new and useful 5 Improvements in Disk-Sharpener; and I do hereby declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to new and useful improvements in apparatus for holding cutting-tools for sharpening disks, &c.; and it consists in various details of construction and combinations and arrangements of parts, 20 as will be hereinafter fully described and then specifically defined in the appended claims.

I illustrate my invention in the accompanying drawings, in which—

25 Figure 1 is a perspective view showing the application of my tool-holding device for holding cutting edges to sharpen disks. Fig. 2 is a perspective view showing a single disk held upon the apparatus. Fig. 3 is a perspective view of the yoke which carries the cutting edges, and Figs. 4, 5, and 6 are detail views.

30 Reference now being had to the details of the drawings, A and A' designate, respectively, two standards which rise from the base A², and B designates a shaft mounted in suitable bearings in said standards.

35 B' designates a spindle which has a threaded circumference mounted in threaded bearings in the tubular shell B², which is secured 40 to the standard A. A wheel B³ is fixed to the end of the spindle B' and is provided with a handle B⁴. The inner end of the spindle B' is tapering and is adapted to engage a socket member B⁵, fitted on the threaded portion of 45 the shaft C.

C' designates disks which are mounted upon the shaft C and are held frictionally against each other by means of a milled nut C⁶, mounted upon a threaded portion of the shaft 50 C. A pinion-wheel E^x is provided, having a hollow-shell hub-section E, which has a bearing in the standard A' and is provided with a collar E⁴, which is mounted upon said hollow hub-section and is held against the outer face

of the standard A' by means of the thumb-screw E⁵.

E' is a pinion-wheel fixed to the shaft B and in mesh with the gear E^x. A gear-wheel F is also fixed to the shaft B and has a series of cog-teeth F', which are in mesh with the pinion-wheel F², fixed to the shaft F³, which is journaled in the standard A'. A handle G is fastened to the shaft F³, being held thereto by means of a set-screw G' and provided to 65 rotate said shaft.

E² is a split clamping member having an L-shaped jaw d, adapted to receive the head C⁴ of the shaft C, and a bolt d² passes through registering and threaded apertures in the upwardly-projecting portions of said clamping 70 member, whereby the latter may be held frictionally to rotate with the hub-section E.

J designates a curved resilient rod, the upper end of which is turned into a loop J' and passes about the shaft B and held thereto by 75 means of a screw or bolt J², a sufficient space intervening between the loop and the shaft to allow said rod to move freely thereon. A movable collar I, having a set-screw I', is mounted upon the curved rod J and has a 80 wing I² projecting therefrom which is adapted to engage the base A² of the frame to steady said rod. Also mounted upon the curved rod is a clamping member K, a detail of which is illustrated in Fig. 3 of the drawings, and 85 through the ends of which passes a screw K', upon which a winged nut K² is mounted. Said clamping member K is adapted to be held at different positions upon the rod J and carries a concaved jaw 1 having oppositely 90 disposed lugs 1², which are apertured, said jaw 1 coöperating with a similar jaw 1⁶, which is concaved, the two forming together a socket for the ball 2 at the end of the rod 3. On said rod 3 is mounted a yoke N, having 95 two bifurcated ends N^x, and in the spaces between the arms of the bifurcated ends are mounted the cutting-knives N', which are held in position by means of thumb-nuts N², which are mounted upon screws N⁶. Said 100 rod 3 passes through a central aperture in said yoke, and upon the rod 3 is a milled nut N⁷, which serves to hold the yoke against a fixed collar 7 upon the rod, while at one end of said rod is fixed an antifriction-roller 4, 105 provided for the purpose of contacting with the face of a disk to steady the apparatus while in operation. Suitable handles O and

O' are fastened to the yoke N', as shown clearly in the drawings, whereby the operator may hold the knives securely against the disks while the latter are operated. By the provision of the resilient rod J it will be understood that the operator may, by pressing upon said handles, cause the rod to yield to throw the knives more forcibly against the disks to expedite the sharpening of the disks, the resilient rod J yielding under pressure to regulate the cutting of the disks.

From the foregoing it will be noted that by the provision of the apparatus described a simple and efficient mechanism is provided whereby either knife may be held against one or the other of the two adjacent disks, as may be desired, and by the adjusting mechanism carrying the knives the latter may be held at different angles to the surface of the disk as the latter is caused to rotate against the knives.

Having thus fully described my invention, what I claim as new, and desire to secure by Letters Patent, is—

1. An apparatus for holding knives for sharpening disks consisting of a frame with standards rising therefrom, a bar connecting

said standards, a disk-carrying shaft, and means for rotating the same, a resilient rod having one end bent to form a loop engaging said bar and movable thereon, a knife-holding yoke, a knife carried by said yoke, and a clamp fixed to said yoke and adjustably held upon said rod, as set forth. 30

2. An apparatus for holding knives for sharpening disks consisting of a frame with standards rising therefrom, a bar connecting said standards, a disk-carrying shaft, and means for rotating the same, a resilient rod having one end bent to form a loop engaging 35 said bar, an adjustable winged collar on said rod, a clamping member adjustably held upon said rod and provided with an integral ball-socket, a knife-carrying yoke, a shaft mounted thereon, a ball at one end of said shaft engaging said socket, and a handle fixed to said yoke, as set forth. 40 45

In testimony whereof I hereunto affix my signature in the presence of two witnesses.

GABRIEL GERARDY.
